UNITED STATES PATENT OFFICE.

FRED C. STORRS, OF CHICAGO, ILLINOIS, ASSIGNOR OF ONE-HALF TO FRANK HOLTON,
OF CHICAGO, ILLINOIS.

BAG-HOLDER.

1,045,211.

Specification of Letters Patent. Patented Nov. 26, 1912.

Application filed October 4, 1906. Serial No. 337,360.

To all whom it may concern:

Be it known that I, FRED C. STORRS, a citizen of the United States, residing at Chicago, in the county of Cook and State of Illinois, have invented certain new and useful Improvements in Bag-Holders, of which the following is a full, clear, and exact specification.

This invention relates to improvements in bag holders, and more particularly to paper bags, and the object of the same is to provide an improved, simple, and efficient device of this character for conveniently holding and retaining a plurality of bags, and from which a single bag may be removed without interfering with the remaining bags.

To the attainment of these ends, and the accomplishment of other new and useful objects, as will appear, the invention consists in the features of novelty, hereinafter more fully described and claimed, and shown in the accompanying drawings illustrating an embodiment of the invention, and in which:

Figure 1 is a perspective view of the counter having this improvement applied thereto; Fig. 2 is a sectional view on line 2—2 of Fig. 1; Fig. 3 is a detail top plan view of one form of bag holder; Fig. 4 is a plan view of the bag holding clamp or clip, and a portion of the clip support; Fig. 5 is a sectional view on line 5—5 of Fig. 4; Fig. 6 is a front elevation of the clip or clamp supporter or holder; Fig. 7 is a detail sectional view of the counter, and a modified form of holder or supporter; Fig. 8 is an elevation of the modified form of holder or supporter; Fig. 9 is a detail sectional view on the line 9—9 of Fig. 8.

Referring more particularly to the drawings, and in which the same reference numerals designate similar parts throughout the several views, the numeral 15 designates the top of a counter which is provided with a depending flange or portion 16, located preferably at the rear thereof, and the depending flange 17 adjacent the flange 16 and parallel thereto. Secured in any suitable manner to the lower face of the flange 16 is a suitable plate or member 18, which is of a width substantially equal to the width of the said flange 16; and the sides thereof are preferably rounded or curved as at 19. A plate or member 20 is provided with a

depressed central portion 21, and the front 55 and rear edge of said depressed portion are preferably rounded or bent, as at 22, in a manner similar to the edges of the plate or member 18. This plate or member 20 is secured in any suitable manner to the plate 60 or member 18 to form a guide or aperture 23 between the plate 18 and the central depressed portion of the plate 20. Any number of these supports or holders thus formed may be employed. 65

A suitable bag holding clip, preferably constructed from a piece of spring metal, may be provided, and this clip is so formed as to produce a coil or projection 24, and extending laterally from said coil or projection are arms 25, the ends of which are deflected toward each other, as at 26, and the extremities 27 thereof are preferably curved and overlap. The convolutions of the coil or projection 24 are preferably spaced from 75 each other, and are so constructed as to be adapted to be brought toward each other to permit of their ready insertion into the aperture 23, and when in position will expand or separate to hold the coil or projection 24 in said aperture. 80

The coil or projection 24 is preferably inserted from the front of the aperture 23, so as to cause the arms 26 to project toward the rear of the counter. Before being inserted 85 into the support or holder, the bags may be inserted into the clip, and the pressure exerted by the bags will cause the arms 25 and 26 to yield and assume the position shown in dotted lines in Fig. 4; the tension of the 90 arms 25 and 26 being sufficient to hold the bags in position and to prevent accidental displacement.

The upper ends of the bags are preferably inserted in the bag-holding clips so that 95 the lower ends will project for some distance above the clips, and when the clip is placed in the support or holder, as shown in Figs. 1 and 2, the bottoms of the bags will assume a position substantially flush with the top 100 of the counter 15.

If desired, and in order to provide additional means for supporting the bottoms of the bags adjacent the top of the counter, suitable guides or holding members 28 may 105 be provided on each side of the bags. These guides or holding members may be of any suitable construction, preferably in the form

of staples driven into the edge of the counter 20, adjacent each side of the bags.

In Fig. 7 is shown a modified form of support or holder. This support or holder is preferably constructed of a piece of flexible wire comprising a body portion 29, and a coil 30, located adjacent one end thereof. The extremity 31 is preferably bent at right angles to the body portion 29. An L-shaped clip or plate 32 is secured to the bottom of the counter 15 in any suitable manner, so that the projecting portion 33 thereof will extend outwardly and be spaced from the bottom of the counter 15, and said forwardly projecting portion 33 is provided with a suitable aperture, adapted to receive the projecting extremity 31 of the supporting member.

The body portion 29 of the supporting member is inserted through the coil 24 of the bag-holding clip, and will hold the bags in such a position that they will rest against the lower edges of the flanges 16 and 17 of the counter, and said supporting member is held against displacement by means of the friction exerted by the extremity 31 in the aperture of the forwardly projecting portion 33, and the pressure of the coil 30 upon the face of the flange 17. In this exemplification of the invention, the bag-holding clip is slightly modified, as shown in dotted lines in Fig. 8, that is, the arms 26 are preferably rounding in a manner similar to the arms 25, so as to prevent the weight of the bag from expanding the arms which would permit the bags to drop out of position.

In the exemplification shown in Fig. 8, the bag-holding clips may be suspended from the ceiling or any other support 34, by means of the hooks 35 which are supported by suitable flexible members 36, which are secured to the hooks 35 and engage suitable hooks 37 secured in the ceiling or support.

In the exemplification shown in Fig. 5, it will be noted that the plate 18 and the base of the reduced portion 21 of the plate 20 are so located in relation to each other that the coils of the convolutions on projection 24 will be compressed, and when the coil or convolution has been entirely inserted in the aperture 23 it will expand to prevent accidental displacement of the bag-holding clip, the rear rounded or curved portions 19, 22, of the plates permitting such an action of the coil. With such an arrangement and holding clip, the bags may be separately removed by grasping the upper end or the bottom of the bag and drawing the same either suddenly or slowly through the clip, and as the number of bags is reduced the flexible arm 26 will exert its pressure upon the sides of the remaining bags to hold the latter in position.

In order that the invention might be fully understood, the details of an embodiment

thereof have been thus specifically described, but

What I claim as new is:

1. In a device of the class described, the combination of a bag-holding clip comprising spaced coils, and a yielding arm on each side of the coil, between which the bags are adapted to be held, a support, and means on the support into which the coil is inserted for holding the clip rigidly in position. 70 75

2. In a device of the class described, the combination of a bag-holding clip comprising spaced coils, and yielding arms on each side of the coils, between which the bags are adapted to be held, a support provided with an aperture, said coils being compressed and inserted into the recess for holding the clip in position, and means whereby the coils will be permitted to expand when in position in the aperture to prevent displacement of the clip. 80 85

3. In a device of the class described, the combination of a bag-holding clip, comprising spaced coils, and yielding arms on each side of the coils, between which the bags are adapted to be held, a support provided with an aperture, the ends of the aperture being enlarged, and said coils being compressed and inserted in the aperture for holding the clip in position, a portion of the coils being adapted to expand when said portion enters the enlargement at the rear of the aperture to prevent displacement of the clip. 90 95

4. In a device of the class described, the combination of a bag-holding clip, comprising spaced coils, and yielding arms on each side of the coils between which the bags are adapted to be held, a support provided with an aperture, said aperture being restricted intermediate its ends, and said restricted portion compressing and receiving the coils for frictionally holding the clip in position. 100 105

5. As an article of manufacture, a bag holding clip constructed of a single piece of metal shaped to form a coil intermediate its ends and with the ends forming arms deflected toward each other and crossing in close proximity to the coil, said arms extending for some distance beyond their crossing point, the free ends of the arms being deflected toward each other and in a direction away from the coil, the extremities of the said free ends of the arms being deflected toward and overlapping each other. 110 115 120

6. As an article of manufacture, a bag holding clip constructed of a single piece of material shaped to form a coil intermediate its ends and with the ends forming arms deflected toward each other and crossing in close proximity to the coil, said arms extending for some distance beyond their crossing point and curving away from the coil, the free ends of the arms being de- 125 130

flected toward each other and in a direction away from the coil, the extremities of the said free ends of the arms being deflected toward and overlapping each other.

- 5 7. As an article of manufacture, a bag holding clip constructed of a single piece of metal shaped to form a coil intermediate its ends and with the ends forming arms deflected toward each other and crossing in
10 close proximity to the coil, said arms extending for some distance beyond their crossing point and curving away from the coil, the free ends of the curved portion

of the arms being deflected toward each other and in a direction away from the coil, 15 the extremities of the said free ends of the arms being deflected toward and overlapping each other.

In testimony whereof I have signed my name to this specification, in the presence of 20 two subscribing witnesses, on this 1st day of October A. D. 1906.

FRED C. STORRS.
